UNITED STATES PATENT OFFICE.

KARL WILLNER, OF GÖRLITZ, GERMANY.

ARRANGEMENT FOR TIGHTENING PISTON-RINGS.

No. 891,317.

Specification of Letters Patent.

Patented June 23, 1908.

Application filed May 25, 1906. Serial No. 318,755.

To all whom it may concern:

Be it known that I, KARL WILLNER, moniteur, a subject of the King of Prussia and German Emperor, residing at Görlitz, Bahnhofstrasse 23, in the Kingdom of Prussia and German Empire, have invented certain new and useful Improvements in Arrangements for Tightening Piston-Rings, of which the following is a specification.

10 The present invention refers to an arrangement for tightening the piston rings in engines with reciprocating pistons particularly in stationary steam engines, locomotives, and the like.

15 The present invention has the purpose to allow of quickly readjusting the piston rings uniformly to all sides, without it being necessary to remove the piston from the cylinder in which it works, or even the cylinder head.

20 In the accompanying drawings a mode of carrying out the present invention is exemplified, Figure 1 being the top view of the upper half of the piston, consisting of two parts joined in a line at right angles to the piston rod. Fig. 2 is a section through the piston and part of the surrounding cylinder, in direction of the piston rod. Fig. 3 is a bottom view of the other half of the piston. Figs. 4 and 5 show the tightening arrangement in 25 plan and side view, Figs. 6 and 7 on a larger scale one of the wedges operating the tightening arrangement in front and top view. Fig. 8 is a side view of the arrangement for operating the wedges, Fig. 9 is a side view of 30 the spanner used for turning said arrangement.

The piston reciprocating in the cylinder 1— is secured by means of screw 2— or other suitable means to the piston rod 3— 40 and consists of two parts 4— and 5— connected with each other by means of screws 6— arranged in a circle concentric with the axis of the piston rod. Part 5— carries a boss 7— having a shoulder at its 45 upper end and a number of eyes 8— corresponding to the connecting screws, by means of which parts 4— and 5— are held together in such a manner that a hollow space 9— is formed for receiving the elastic piston rings and the below described arrangement for tightening said piston rings. In place of several piston rings also one single elastic piston ring can be used.

50 The piston rings 10— are continuously forced outwards by means of an elastic ring 11— made of steel or other suitable mate-

rial, and cut open at two places diametrically opposite each other, said ring resting against the inside surface of the piston ring. The ends of the ring 11— which meet, are suitably made to overlap in a manner shown in Fig. 5 their joints being covered on the inside by means of fish plates 11'— riveted to one of the ends and lying loose against the other. Instead of a ring split in two parts 60 also rings split into several parts can of course be employed, when however all parts should be of equal length. Ring 11— is connected by means of a number of radially arranged and suitably exchangeable springs 65 12— with two or more concentrically to the piston center provided straps 13— which have radial flanges at their ends 14—. In the design shown in the drawings 8 such springs 12— are provided 70 which are suitably arranged between each two of the screws 6—. The flanges 14— of the straps 13— form wedge shaped guides pointing towards the center of the piston to take the adjusting wedges 15—, 75 Fig. 6 and 7, the inside edges of said flanges resting each pair together against surfaces 16— straight and parallel to the axis of the piston rod, which surfaces are suitably provided on the boss 7— of the piston, Fig. 1; 80 on the wedges being tightened these flanges will be forced out. The wedges 15— have a trapezoidal section and have shoulders 17— on top and bottom, intended as guides for the wedges in corresponding 85 grooves 18—, 19— of the piston parts 4—, 5—. The wedges 15— are moved by means of eccentrics 21—, 21— on bolts 20—, 20— pivotally arranged in the piston parts 4—, 5—, Fig. 8, said 90 eccentrics 21— working against the outer surfaces of wedges 15. The upper ends of the bolts 20— are made as square heads 22— to take a socket wrench 23—, Fig. 9, for turning the bolt 20— or the eccentric 95 21— respectively. At its lower end the bolt 20— carries a ratchet wheel 24— arranged in a suitably provided recess 25— in the part 5—, and meshing with a catch or pawl 26— under action of a spring, so 100 that eccentric 21— and bolt 20— are prevented from turning back.

In the cylinder head 27— holes are provided corresponding with the eccentric spin- 110 dles, said holes being ordinarily closed by means of screw plugs 28— and when open allowing of inserting the wrench 23— for

turning the eccentric and thereby tightening the piston rings, without the cylinder heads having to be removed. On the cylinder head or on the part —4— a graduation can 5 be provided, which will facilitate a uniform adjustment of the eccentric the wrench —23— being provided with a toothed wheel —29— Fig. 9, the division of which and the pitch circle of which is equal to that of the 10 ratchet wheel —24—, so that it can be ascertained from outside, by how many teeth the eccentric has been turned.

On turning the eccentrics —21— the 15 wedges —15— are moved between the flanges —14— of straps —13— towards the inside and thereby bend the said straps and move them towards the outside so that by 20 means of the springs —12— and the elastic ring —11— the packing rings —10— are forced quite evenly to the wall of the cylinder all around. When after some time the packing rings are worn, they can be easily readjusted without having to remove the cylinder head.

25 Owing to the constant and uniform pressure of the packing rings, a considerable amount of coal and steam is saved, the walls of the cylinder is not worn one sided or unevenly, and as the packing has nowhere to do 30 any overwork, it will wear very slowly, and so greatly reduce the costs for repairs. Furthermore the pistons are more easily fitted into the cylinder.

Having now described my invention, what 35 I claim and desire to secure by Letters Patent of the United States is:

1. In combination with a two-part piston for reciprocating engines packing rings supported by a plurality of radial springs, circular straps supporting the inner ends of said 40 springs, converging flanges provided at the ends of said straps and means for forcing outward or relieving said flanges substantially as described.

45 2. In combination with a two-part piston for reciprocating engines packing rings supported by a plurality of radial springs, circular straps supporting the inner ends of said springs, converging flanges provided at the 50 ends of said straps guiding surfaces provided for the inner edges of said flanges at the boss

of the piston and means for forcing outward or relieving said flanges, substantially as described.

3. In combination with a two-part piston 55 for reciprocating engines packing rings supported by a plurality of radial springs, circular straps supporting the inner ends of said springs converging flanges provided at the ends of said straps guiding surfaces provided 60 for the inner edges of said flanges at the boss of the piston, wedges guided in grooves of the piston intended to be pressed between the said flanges, and means for displacing said wedges radially, substantially as de- 65 scribed.

4. In combination, with a two-part piston for reciprocating engines rings supported by a plurality of radial springs, circular straps supporting the inner ends of said springs, 70 converging flanges provided at the ends of said straps guiding surfaces provided for the inner edges of said flanges at the boss of the piston, wedges guided in grooves of the piston intended to be pressed between the said 75 flanges, eccentrics mounted upon bolts within the hollow piston and pressing upon the outer faces of said wedges and means for turning and tightening said eccentrics, sub- 80 stantially as described.

5. In combination with a two-part piston for reciprocating engines packing rings supported by a plurality of radial springs, circular straps supporting the inner ends of said springs, converging flanges provided at the 85 ends of said straps guiding surfaces provided for the inner edges of said flanges at the boss of the piston, wedges guided in grooves of the piston intended to be pressed between the said flanges, eccentrics mounted upon bolts 90 within the hollow piston and pressing upon the outer faces of said wedges, the said bolts being provided with square heads at their free ends and with ratchet wheels meshing with a pawl, substantially as described. 95

In testimony whereof I have hereunto set my hand in the presence of two witnesses.

KARL WILLNER.
